(57) **CLAIM**

The ornamental design for a license plate frame, as shown and described.

DESCRIPTION

FIG. 1 is a perspective front view showing our new design for a license plate frame.

FIG. 2 is a perspective back view of the license plate frame of the present invention.

FIG. 3 is a front view of the license plate frame of the present invention.

FIG. 4 is a back view of the license plate frame of the present invention.

FIG. 5 is a top view of the license plate frame of the present invention.

FIG. 6 is a right side view of the license plate frame of the present invention, the left side view being the mirror image thereof; and,

FIG. 7 is a bottom view of the license plate frame of the present invention.
